UNITED STATES PATENT OFFICE.

WALTER ANDERSON TAYLOR, OF NEW ORLEANS, LOUISIANA, ASSIGNOR TO
TAYLOR BROTHERS, OF SAME PLACE.

STEAM-TRAP.

SPECIFICATION forming part of Letters Patent No. 400,718, dated April 2, 1889.

Application filed October 23, 1888. Serial No. 288,939. (No model.)

To all whom it may concern:

Be it known that I, WALTER ANDERSON TAYLOR, a citizen of the United States, residing at New Orleans, in the parish of Orleans 5 and State of Louisiana, have invented new and useful Improvements in Steam-Traps, of which the following is a specification.

This invention relates to the steam-trap constituting the subject-matter of Letters Patent 10 No. 326,347, issued September 15, 1885, to W. W. Taylor, and has for its object to provide novel means whereby the stroke of the actuating-lever may be adjusted at will to vary the permanent water-level in the condensed-water 15 vessel.

The invention consists in the features and combination of devices hereinafter described and claimed, reference being made to the accompanying drawings, in which—

20 Figure 1 is an elevation of a steam-trap embodying my invention. Fig. 2 is a central vertical section, partly in elevation. Fig. 3 is a detail view of the adjustable bracket-rest. Fig. 4 is a detail plan view of the relief stuffing-box. Fig. 5 is a central vertical section of the same.

In the said drawings, the reference-letter A designates a receiver for condensed water connected at B to a manifold, C, to which manifold 30 a number of connections, D, may be made to a number of steam-coils. The connection-pipes D are shown broken off. The manifold enables the trap to be taken apart without disconnecting the pipe-connections by breaking the flange-joint at B. At E is the outlet-valve, some distance from the bottom. The space in the receiver below the valve E serves as a trap for sediment that may enter the receiver with the water of condensation from

40 the steam-coils. Inside the receiver A is a weighted float, F, which is connected with the lever G by the chain H and rod I that passes through the stuffing-box J, and is connected at its lower end to the float F. The lever G is fulcrumed upon the upright K, bolted to the receiver A, and said lever is provided with a counterbalance-weight, L, that may be adjusted upon the lever G to balance the float F.

The valve-stem M is connected to the lever 50 G between the actuating end and the fulcrum

N by means of a rigid rod, O, with a lug at its lower end through which the valve-stem passes, whereby it can be adjusted by means of jam-nuts m above and below, so as to set the valve E at the proper point.

P denotes an adjustable stop-bracket and lever-guide, which can be raised or lowered and set at any point by means of set-screws e, thus changing the position of the lever G to any point above or below the center horizontal 60 plane, enabling the water to be carried at various permanent levels above the discharge-valve E. The stop-bracket and guide consist of the parallel arms a, having a stem, c, adjustable in the bracket b, in which the stem 65 c works. The bracket is bolted to the top of the trap-cover d.

Upon the cover d of the trap is mounted a stuffing-box through which the stem I passes. This box is provided with the usual packing-chamber, R, forming part of a gland, R', which has a female thread turning on a nipple, S, through which the stem I passes. This nipple forms part of a relief-box, Q, having an outlet, S', which communicates with the outlet 75 E. If any leakage takes place around the stem I, it will pass off through the pipe S' and discharge-valve E. This form of stuffing-box not only requires less packing, but need not be so tightly screwed up, and therefore exposes the stem I to less friction. It has thus less liability of sticking or gumming and works more easily and with less expenditure of power, and is applicable to any purpose 80 where stuffing-boxes are required.

In operation, the weight F being properly adjusted upon the lever G, the water of condensation entering the receiver A will raise the float F until it is lifted to the upper dotted line position representing the upper water-level, which is some distance above the valve E, at which point the valve E will begin to open by the further movement of the lever G, caused by the continued formation of the water of condensation, effecting the further lifting of the float F and the opening of the valve E full way, which will permit the surplus water in the receiver to pass out of the valve E and faster than the formation of the water of condensation, the water continuing to be dis- 95 roc

charged until the float has again descended to its former lowered position, about four inches above the valve E, until another surplus of water accumulates in the receiver, when the 15 action will be automatically repeated.

From the foregoing it will be seen that the float will be kept in a constant state of motion to prevent the liability of the float sticking, as in practice is found to occur when the float 20 is at any time in a state of rest, which is the case where the action of the parts is such that a gradual or continuous discharge of the water of condensation takes place. Further, the valve E is always closed at a point below the low-water level to prevent the escape at any time of steam, whereby, together with the maintenance of the float in a constant state of action, not allowing it an opportunity to become wedged or clogged nor at any time to be exposed to the action or pressure of the steam, the valve will be preserved for a longer time in actual use. All sediment can be 25 blown out at blow-off pipe T. By using a heavy float F, counterbalanced by a heavy weight L, I get a positive action of the trap, as the water in receding from the float F will give a great difference in weight over the counter-balance L, and vice versa, thus securing a positive action of the trap. By the use 30 of a manifold, C, a great many coils can be drained through a single opening in the receiver.

The adjustable stirrup P can be set to regulate the rise and fall of the float F inside of fixed points.

What I claim is—

1. In a steam-trap, the combination, with a condensed-water vessel having a discharge valve located outside thereof below the water-level, a weighted float in the vessel having a stem 40 rising through the top thereof, a lever pivoted above and outside the casing and connected with the float-stem, and an external rigid rod connecting the lever to the stem, of the external valve for moving the valve in unison with any movement of the lever, and a lever-stop bracket, and guide rising from a support on the top of the vessel and adjustable lengthwise in a vertical plane on said support to enable the water to be carried at different 45 levels above the discharge-valve, substantially as described.

2. In a steam-trap, the combination, with a condensed-water vessel having an external discharge-valve, a lever pivoted above the vessel and connected with the float, and an external rigid connection between the lever and the valve-stem which moves the valve in unison with any movement of the lever, of a supporting-bracket rising from the top of the vessel, a stop-bracket and guide for the lever, having a stem movable lengthwise in a vertical plane in the supporting-bracket, and means for rigidly locking the stem and supporting-bracket together, substantially as described. 55

In testimony whereof I affix my signature in presence of two witnesses.

WALTER ANDERSON TAYLOR.
